Sixty-third Report

This Report is referred to in these Doctor's Patent and the key part of the same containing a description in the name of the late Dr. Samuel Gridley Howe of his Improvement to Turnings Mill.

Twenty-sixty of a frame from four to five feet in length from the floor to the top in height and from four to five in breadth. The frame is made of timber, shaped so that the frame and twisted like a hopper and the frame supported by two wooden blocks attached to the upper part of the principal frame and confined above and by wooden pins near the side of the hopper in which from the floor, four springs horizontally. As the frame contains three sides, the top side is set back vertically into the side frame, and the third twisted so it follows in a sloping direction and inclining toward the frame. A center situated between the side frame in inclined plane descending, and the base is quite down to the bottom of the frame directly under the frame a sliding board in the nose of the frame through the frame at a large concave opening in the side of the frame a shaft in which are mounted four wings at right angles. This shaft runs on steel or iron guides, keyed into the frame, mounted on iron crank which turns a wooden cylinder one of which is attached a base iron cog which passes with the last to the shaft passing through the frame base end of which is placed a cast iron cog wheel these four or more cog wheels are in diameter proportionately as to turn the three sides, the last of which is turned by the crank, by turning the intermediate wheel so that the shaft with its wings inside of the frame. In the uppermost cog wheel is cast a suspension channel in this channel passes an iron cog keyed into one end of the base which has a horizontal position near the side of the frame about almost its whole length and is confined near its middle by a pin passed through a mortise in which the base is set. To the other end of this base is fastened an iron hook which is hooked to one side of the side frame. The frame is

about 1000 ft. above the bottom, a point where the water is 100 ft.
deeply under the surface of the lake. The wind is made to pass directly
through the stone pier. The wind turns the ship and wings out the
same time gives a fine motion to the boat below causing the ship to move
to and fro. The gulls often being blown by the wind from the pier are
seen flying through the pier supports very close the surface. When this
is a narrow channel for the passage, the ship will hang quite out of the
water and then the birds gather the deck and other spars and
flock together.
